UNITED STATES PATENT OFFICE

KENNETH K. SIKES, OF TOLT, WASHINGTON

HEATER AND STERILIZER

Application filed April 30, 1928. Serial No. 273,896.

This invention relates to a device particularly suitable for the use of farmers and dairymen in providing hot water in barns, or other outbuildings, and also for sterilizing 5 milk utensils, or the like, through the actions of water and steam.

Heretofore devices have been produced for sterilizing such utensils, but they have been more or less complicated in construction, and, 10 in view of their cost to manufacture, have been offered at prices which in many instances proved prohibitive to those who had use for same. None of said devices, so far as known to me, are designed or adapted to 15 also perform the double duty of furnishing hot water for use.

The objects of my invention, generally stated, are, to provide a heater and sterilizer which performs said functions and makes 20 conveniently available means for sterilizing such utensils and supplying hot water in the environment mentioned; and, to afford such a device which, while utilizing an immersion type of water heater, nevertheless, has few 25 and simple parts, thereby permitting it to be produced and sold at a relatively low cost.

Other objects may appear as the description of the invention progresses.

In the accompanying drawing—

30 Figure 1 is a view, in elevation, of the device;

Fig. 2, a vertical section of the same; and,

Fig. 3, a cross section, drawn on the line 3—3, of Fig. 1.

35 Referring more particularly to the drawing, the device consists of a cylindrical container, generally denoted as 1, formed of a plurality of wooden staves 2, secured in place by metallic bands 3, and provided with a bottom portion 4, also of wood.

40 A cover, having a circular and wooden body portion 5, reenforced by a wooden circular portion 6, reduced in diameter, is provided on its lower surface with a covering of sheet copper 7. Said surface is of a form complementary to the open top of the container, the portion 6 obviously holding the cover against lateral displacement, and said copper affording a lining which strengthens 45 the cover against warping and is non-rusting.

when in contact with water or steam. A handle for the cover, secured to said body portion, is designated as 8.

A false wooden bottom, consisting of a plurality of cleats 9, supported by a pair of transversely extending cleats 10, secured thereto, is disposed within the container, in spaced relation with the adjacent vertically extending surface and elevated from the bottom thereof, as indicated in Fig. 2, the same being designed to support utensils to be treated.

For the purpose of supplying heat to the device I utilize an immersion type of electric heater, the heat-dispensing member thereof, 65 operatively disposed in the container and below the false bottom, and the plug connected with said member and socketed in the container, being denoted as 11 and 12 respectively. The wires 13 connected with the plug 70 indicate, as is evident, the usual means through which electrical communication is established with the heating member from the source of supply. The electric heater thus employed is designed to be a conventional one of the variety to which it belongs, and its construction consequently is no part 75 of my invention. 14 denotes a faucet, through which water may be drawn from the container.

80 A cementitious coat of heat-insulating material 15 is applied to the outside of the container, in a plastic condition, and smoothed down, as is more particularly shown in Fig. 2. The composition, thus applied, conserves the heat generated by the heater, and will effect a considerable saving in the electrical energy required to operate it in connection with the device. It also permits the staves and metallic bands to be covered, thereby im- 85 parting to the container a more pleasing appearance.

I prefer to use a composition which includes asbestos as one of its ingredients, and, as will be obvious to those skilled in the art, any one of a number of heat-insulating compositions is suitable for the purposes intended.

90 The desired quantity of water having been placed in the container and heated to the required temperature, through the instrumen- 95 100

talities shown and described, hot water, as is obvious, may be drawn from the faucet for use and utensils placed on the false bottom, where they will be subjected to the cleansing and sterilizing actions of water and steam.

5 In the present embodiment of the invention I have disclosed a structure which, in its interior aspect, presents a construction which is practically all of wood, thereby permitting the utensils, while being treated, to come in contact only with parts thereof which are non-rusting and non-corrosive, and enabling it to be readily cleaned and kept in a sanitary condition.

10 15 I claim:—

1. A water heater and sterilizer, comprising a wooden container, a cementitious covering of heat-insulating material around the container, a cover for the container, a false wooden bottom, having openings to permit the circulation of water and steam therethrough, a hot-water faucet, and an immersion type of electric heater operatively disposed within the container and below the

20 25 false bottom.

2. A device for supplying hot water and sterilizing dairy utensils by steam; comprising a container, a heat-insulating medium extending exteriorly of the container, a cover 30 for the container, an elevated support disposed in the bottom of the container adapted to permit the circulation of water and steam therearound, a hot-water faucet and an immersion type of electric heater operatively disposed within the container.
